(57) **CLAIM**

The ornamental design for a top sizer, as shown and described.

DESCRIPTION

FIG. 1 is a front elevational view of a top sizer showing my new design in a position of use, the hanger fragmentarily shown in phantom line illustrating environment only and not forming a part of the claimed design;

FIG. 2 is a rear elevational view thereof;

FIG. 3 is a top plan view thereof;

FIG. 4 is a bottom plan view thereof; and,

FIG. 5 is an end elevational view thereof, the other end being a mirror image thereof.

FIGS. 2-5 are shown on an enlarged scale.

1 Claim, 2 Drawing Sheets

FIG. 3

FIG. 2

FIG. 4
